(57) **CLAIM**

The ornamental design for a toddler busy board as shown and described.

DESCRIPTION

FIG. 1 is a front perspective view of a toddler busy board, showing my new design in first configuration of use;

FIG. 2 is a top view of a toddler busy board, showing my new design in an open configuration of use;

FIG. 3 is a front perspective view of a toddler busy board, showing my new design in second configuration of use, wherein the centre pages are detached and therefore not shown;

FIG. 4 is a front perspective view of the toddler busy board, shown in a fully opened state, wherein the centre pages are detached and therefore not shown;

FIG. 5 is a rear perspective view thereof;

FIG. 6 is a front elevation view of a first page of the toddler busy board; the first page is shown separately for ease of illustration;

FIG. 7 is a rear view thereof;

FIG. 8 is a front elevation view of a second page of the toddler busy board; the second page is shown separately for ease of illustration;

FIG. 9 is a rear view thereof;

FIG. 10 is a front elevation view of a third page of the toddler busy board; the third page is shown separately for ease of illustration; and,

FIG. 11 is a rear view thereof.

The claim is directed to the collective appearance of all elements shown.

The dash-dash broken lines shown in the drawings depicts portions of the toddler busy board that form no part of the claimed design. The dash-dot-dash broken lines in the drawings depicts stitching on the toddler busy board and forms no part of the claimed design.

1 Claim, 11 Drawing Sheets
